CLEANER FOR COTTON LINTERS

Arthur J. V. Ware, Memphis, Tenn.

Application June 30, 1938, Serial No. 216,672

9 Claims. (Cl. 19—67)

This invention relates to apparatus for cleaning cotton linters by separating out dust and other small particles therefrom, linters being a material which is so light that gravity and centrifugal force have little effect during the period when it is within the machine, either for effecting its movement through the machine or its discharge therefrom.

It further relates to apparatus in which a whirling and downwardly moving spiral column of air is set up to project the heavier particles of dust centrifugally against and through the screen, and to transfer the lighter particles of lint downward and eject them tangentially from the machine.

The objects of the invention are:

To provide an apparatus for accomplishing the efficient separation of dust and other finely divided trash from an inherently lighter material which is to be cleaned and recovered.

To provide an apparatus which will establish a downwardly moving spiral column of air for movement of an extremely light material and its discharge tangentially from the device.

To provide an apparatus in which a mixture of an extremely light, and comparatively heavier, finely divided materials is separated and discharged in which rapid rotation and gravity acting on the mixed materials set up a current of carrying air moving spirally downward for eventual discharge tangentially of the extremely light material.

To provide an apparatus of the character described which is simple in construction and readily dismountable for the removal and replacement of parts thereof subject to wear.

To provide a method for separating an extremely light and relatively heavier, finely divided materials which includes setting up in the combined materials by rotary movement and gravity centrifugal action for removing the heavier materials and concurrently establishing a spirally, downwardly moving revolving column of air for accomplishing the discharge of the extremely light material by air flow.

The means by which the foregoing and other objects are accomplished and the method of their accomplishment will readily be understood from the following specification on reference to the accompanying drawings, in which:

Fig. 1 is a vertical elevation of the device, a portion of which is cut away in section.

Fig. 2 is a sectional plan taken on the line II—II of Fig. 1; and,

Fig. 3 is an elevation half in section taken on

the vertical center line of the apparatus showing a modified form of head and inlet construction.

Fig. 4 is a side elevation of a battery of the machines connected in series.

Referring now to the drawings in which the various parts are indicated by numerals:

The apparatus comprises a vertically disposed imperforate casing 10, preferably cylindrical, having an imperforate bottom 11, the casing preferably extending below such bottom and being cut away at intervals to provide legs 12 for the support of the apparatus, these legs preferably being secured to an angle iron stiffener ring 13, as by rivets 14, or by welding, the ring also serving as a means to increase the base area 15 and permit ready securing to a suitable foundation.

Adjacent the bottom 11 the casing is provided with a dust discharge opening 15 having a dust discharge chute 16 leading therefrom, one side 20 of this chute preferably forming a tangential continuation of the casing 10. The upper end of the casing terminates in an annular ring 17 formed of angle iron, having its horizontal leg 18 upward and substantially flush with the top of the casing. The casing is closed by a head which comprises an annular disc 19 secured as by welding 20 to an annular ring 21, complementary to the annular ring 17, this ring being also of angle iron and having its horizontal leg 22 at the bottom. 23 are bolts which secure the two rings together. 24 is an inlet pipe conforming in size to the opening in the annular disc 19, secured to this disc as by an annular weld 25, and extending upward from the disc. 26 is a stiffener ring around the pipe 24.

30 is an annular disc having a central opening in excess of the sizes of the pipe 24 and the opening in the disc 19. This disc has its outer portion disposed between the flanges 17 and 21 and is clamped between the legs 18 and 22 of these flanges by securing bolts 23. 31 is an annular ring of angle iron having its vertical leg substantially flush with the opening in the disc. 32 is a cylindrical screen which is secured to the disc 30 and angle iron 31 and extends downward therefrom toward, but not to, the bottom 11 of the casing. At its bottom end the cylindrical screen 32 contacts the cylindrical side wall 33 of a pan or tray having a bottom 34, both of which 50 preferably are imperforate. The cylindrical screen 32 may extend within the cylindrical wall 33, but preferably for ease in assembling, extends there-outside, and snugly fits the exterior of such wall, but need not be secured thereto. 55

35 is a stiffener ring surrounding the cylindrical wall 33, and 36 one of a plurality of guiding fingers which assist in positioning the lower end of the screen 32 when it is being put into place. 5 37 are bolts passing through the cylindrical wall 33 and extending outward through the casing wall 10 which support and steady the pan, these bolts being secured by nuts 38. 39 is a discharge opening in the wall 33 from which opening a 10 lint discharge chute 40 extends, one wall 41 of this chute being tangential to the wall 33. The chute 40 extends through a suitable opening in the casing 10 and is preferably secured to the casing as by welds 42. 15 43 is a beater shaft concentric with the cylindrical screen 32 and having beater arms 44, which extend adjacent the screen. The shaft is journaled at its lower end in a step bearing 45 which is carried by the bottom 11 of the outer casing and at the top in a bearing 46, this latter bearing being supported by radially extending bolts 47, one only of which appears in the drawing. These bolts are each disposed in a slot 48 in the vertical leg of the angle 31, and are 20 clamped in such slots by nuts 49.

The lower end 50 of the shaft is reduced in size and projects below the bearing 45. 51 is a pulley secured on the shaft end 50 and caused to turn therewith as by a key 52. 53 is a collar secured 25 on the shaft 43 above the bearing 46 as by a set screw 54. 55 is one of a pair of arms which extend in diametrically opposite directions from the collar 53 and are turned downward in proximity to the bolts 47 to prevent accumulation of material thereon. 56 is a rod which is threaded from one end past its center and is secured through the shaft 43, forming arms which project in opposite directions from the shaft above, but adjacent to the casing bottom 11, these arms 30 causing discharge of the dust screened out through the flue. 40

60 is an electric motor carrying a pulley 61 which is connected by a belt 62 with the pulley 51.

In Fig. 4, 10—A, 10—B, 10—C, are the casings 45 of three machines connected in series. 65 is a feed chute discharging into the inlet pipe 24—A of the first machine. 40—A is the lint flue discharging therefrom, and 16—A the dust flue. The dust flue 16—A discharges through a pipe 50 or chute 66—A into the inlet pipe 24—B of the second machine. 40—B is a lint flue and 16—B the dust flue which latter discharges through the chute 66—B into the third machine. 40—C is the lint flue discharging from this machine, 55 and 16—C the dust discharge flue. It will be obvious that more or fewer of the machines may be connected in series as occasion demands.

It will be noted that the feed chute 65 discharges into the first machine but is not connected thereto so that an air supply may enter the machine around and independent of the air entering with the material fed in, and it will be noted that the same conditions exist so far as the additional chutes are concerned.

65 In Fig. 3 a modified form of the device is shown in which the head of the machine is closed except for the inlet pipe, which pipe may lead into the machine from a more or less remote collector of material, not here germane and not here shown. In this modification which also includes modification in detail, applicable to the previously shown form of the machine, 10—A is the casing, the upper end of which is outwardly turned to 70 form an annular flange 18—A. 23—A are the 75 bolts which secure the head in place. 22—A is

the head flange which is secured to the casing flange by the bolts 23—A. 19—A is the annular inwardly extending disc portion of the head, and 24—A the upwardly extending inlet pipe, the upper end of which pipe is closed by a plate 70, 5 here shown as integrally secured as by welding. This plate carries the upper bearing 46—A for the shaft 43—A. 72 is a feed pipe here shown as leading horizontally into the side of the pipe 24—A, though the point of entrance and direction of entrance is not material. 32—A is the screen and 30—A the supporting member which may be clamped as before between the flanges 18—A and 22—A of the casing and head respectively, this supporting member being here shown 15 as having an integral upwardly turned flange 73 instead of the angle flange heretofore shown. 44—A is one of the beater blades.

Where this closed head type of machine is used in a battery of machines the pipe, as the 20 pipe 66—A connecting one of these machines to the next, ordinarily enters a similarly closed head in much the same manner as does the feed pipe 72.

It will be understood that the mesh of the 25 screen 32 is selected to suit the varying grades of material which are to be treated, and, that where a battery of machines is connected up in series, as shown in Fig. 4, that usually the 30 screen of the first machine will be of a relatively coarse mesh and the screen of each succeeding machine of finer mesh.

In operating the machine the shaft 43 is driven at a rapid rate of speed, usually around 1100 35 R. P. M. The dirty linters are fed into the top of the casing and descend by gravity into the machine. Any lint and dust tending to accumulate on the bolts 47 is brushed off by the arms 55 and drops into the machine. As the dust laden lint enters the zone of the beater blades 40 44, it is inherently heavy and is readily picked up and whirled around the interior of the screen 32 by the blades. The combined action of the weight of the material and the whirling action, due to the motion of the blades, sets up a spirally 45 downward and rotary movement of the material and a similar spirally and downwardly rotating current of air within the screen. The heavier dust and other particles are thrown by centrifugal action against and through the screen and 50 into the exterior casing. As the materials descend within the screen cylinder, more and more of the dust is driven out and the resulting cleaner 55 dust becomes much lighter and less controllable. The spirally downward current of air set up however carries the lint downward and, in connection with the direct blade action, discharges it outward through the lint flue 40, from which it may be led to a suitable receptacle. The dust 60 passing through the meshes of the screen 32 drops downward and is ejected by the rotary motion of the arms 56 through the dust flue 16 65 from which it may also be collected.

Should a battery of the machines be used, the 70 meshes of the screen of the first machine are usually made so coarse that a large amount of the lint is carried through these meshes with the dust and such dust and lint is discharged through the flue 66—A into the next machine and from this next machine the dust and lint discharge passes through the chute 66—B into the 75 third machine. The lint discharges are individually collected from each of the three machines, and are usually of progressively lower 80 grade.

If, from time to time, wear should make replacement of parts necessary, or it should be desired to substitute other and different parts, as a coarser or finer screen, such replacement is made comparatively simple by the construction here shown. As a first step, the bolts 23 are removed and the head, including the plate 19, ring 21 and inlet pipe 24 are lifted off as a unit; the set screw 54 is loosened and the collar 53 and arms 55 are removed. The nuts 49 holding the bolts 47 are loosened and the bearing 48 removed. The screen 32 and its supporting plate 30 and flange 31 is then free and may be lifted out. Should it be desired to remove the shaft 45, the pulley 51 is removed and the shaft turned until the unthreaded end of the rod 46 is alined with the chute 16. The rod is then unscrewed from the shaft, the opposite threaded portion permitting such action and the shaft is free to be lifted out and overhauled as may be found necessary.

In replacing the parts they may obviously be replaced in reverse sequence. It is preferable, however, in such replacements that the screen be first put in place. To do this the screen is lowered until, guided by the fingers 36, it rests on top of the cylindrical wall 33. A tool having a point similar to an ordinary screw driver may then be used, within the accessible center of the screen, to move inwardly extending parts of the screen outward so that they will line up with the outside of the cylindrical wall 33, until eventually the entire circumference is alined and the screen may slip down over this wall and into place.

I claim:

1. A cleaner for an inherently light fibrous material as cotton linters, including an imperforate casing, having an imperforate bottom centrally apertured for a shaft and a lateral discharge chute contiguous to said bottom, an imperforate head having a centrally disposed inlet opening; means securing said head to said casing, a shaft extending vertically upward through said aperture, substantially to the top of said casing, said shaft having a plurality of blades extending substantially at right angles therefrom, bearings journaling the upper and lower ends of said shaft, a cylindrical screen open at the top and of greater diameter than said inlet opening, disposed in said casing around said inlet opening and substantially concentric with said shaft, said screen depending from the upper end of said casing and terminating above said casing bottom, and having an imperforate bottom closing its lower end; a tangential discharge chute leading from said screen contiguous to its said bottom, at least one set of said blades extending from said shaft between the bottoms of said screen and said casing and the remainder thereof being within said screen; said chutes leading in the same rotational direction from said screen and casing; and means for driving said shaft at a high rate of speed in said casing in said rotational direction, whereby to cause movement of said material against said screen for cleaning separation thereby, and to set up cyclonic air flows for the segregated transfer and discharge of said material and the refuse cleaned therefrom, through said chutes.
2. A cleaner for an inherently light fibrous material as cotton linters, including an imperforate cylindrical casing, having an imperforate bottom centrally apertured for a shaft and a tangential discharge chute contiguous to said bottom, an imperforate head having a centrally dis-
- posed inlet opening; means securing said head to said casing, a shaft extending vertically upward through said aperture, and substantially to the top of said casing, said shaft having a plurality of blades extending therefrom, bearings journaling the upper and lower ends of said shaft, a cylindrical screen open at the top and of greater diameter than said inlet opening, disposed in said casing around said inlet opening and substantially concentric with said shaft, said screen depending from the upper end of said casing and terminating above said discharge chute and having an imperforate bottom closing its lower end, a tangential discharge chute leading from said screen contiguous to said bottom, and means for driving said shaft at a high rate of speed in said rotational direction, whereby to cause movement of said material against said screen for cleaning separation thereby, and to set up cyclonic air flows for the segregated transfer and discharge of said material and the refuse cleaned therefrom, through said tangential chutes.
3. A cleaner for an inherently light fibrous material as cotton linters, including an imperforate cylindrical casing, having an imperforate bottom centrally apertured for a shaft and a tangential discharge chute contiguous to said bottom, an imperforate head having a centrally disposed inlet opening; means securing said head to said casing, a shaft extending vertically upward through said aperture, and substantially to the top of said casing, said shaft having a plurality of blades extending therefrom, bearings journaling the upper and lower ends of said shaft, a cylindrical screen open at the top and of greater diameter than said inlet opening, disposed in said casing around said inlet opening and substantially concentric with said shaft, said screen depending from the upper end of said casing and terminating above said discharge chute, a pan having a cylindrical wall forming a continuation of said screen, an imperforate bottom closing its lower end, and a tangential discharge chute leading from said wall contiguous to said bottom, and means carried by said casing supporting and centering said pan, at least one set of said blades being between said casing and pan bottoms; said chutes leading in the same rotational direction from said screen and casing; and means for driving said shaft at a high rate of speed in said rotational direction, whereby to cause movement of said material against said screen for cleaning separation thereby, and to set up cyclonic air flows for the segregated transfer and discharge of said material and the refuse cleaned therefrom, through said tangential chutes.
4. In a cleaner for cotton linters, which includes a cylindrical casing, outwardly flanged at its upper end a cylindrical screen within said casing concentric therewith and annularly spaced therefrom, and a shaft concentric with said casing and said screen; an inverted cup shaped head having an encircling flange, supported by said casing flange, disposed thereabove, bolts removably securing said flanges together, said head having a concentric inlet opening therethrough, a member disposed between said flanges and removably secured by said bolts, said member having a central opening conforming to the exterior of said screen and having an upwardly turned flange

- around said opening, said screen being secured to and depending from said member and said flange being downwardly slotted at intervals; a bearing journaling the upper end of said shaft, threaded rods secured to said bearing and extending outwardly each into a respective one of said slots, and pairs of nuts on said rods disposed on opposite sides of said flange to removably secure said rods and said bearing.
5. In a cleaner for cotton linters, which includes a cylindrical casing, a cylindrical screen within said casing concentric therewith and annularly spaced therefrom, and a shaft concentric with said casing and said screen; an inverted cup shaped head supported by said casing, and means removably securing said casing and a head together, said head having a concentric inlet opening therethrough, a member disposed between said casing and head and removably secured by said securing means, said member having a central opening conforming to the exterior of said screen and having an upwardly turned flange portion substantially contacting said head, said screen being secured to and depending from said member.
10. 6. A cleaner for an inherently light fibrous material as cotton linters, including an imperforate, vertical, cylindrical casing having a bottom centrally apertured for a shaft and a tangential discharge chute contiguous to said bottom, a cylindrical screen disposed and rigidly supported within said casing, and concentric therewith, said screen having an open top, a bottom centrally apertured for a shaft, and a tangentially disposed discharge chute adjacent said bottom, said screen bottom and chute being spaced above said casing bottom, and said screen chute extending through a side wall of said casing; a suitably journalled shaft extending through said apertures and concentric with said screen, said shaft having a plurality of blades extending therefrom, one set of said blades being disposed in the space between said casing and screen bottoms; said chutes leading in the same rotational direction from said screen and casing; and means for driving said shaft at a high rate of speed in said rotational direction, whereby to cause movement of said material against said screen for cleaning separation thereby, and to set up cyclonic air flows for the segregated transfer and discharge of said material and the refuse cleaned therefrom, through said tangential chutes.
15. 7. A cleaner for cotton linters, including an imperforate casing, having a bottom centrally apertured for a shaft, and a lateral discharge chute contiguous to said bottom, a head having a centrally disposed inlet opening; means securing said head to said casing, a shaft extending vertically upward through said aperture, substantially to the top of said casing, said shaft having a plurality of blades extending substantially at right angles therefrom, bearings journaling the upper and lower ends of said shaft, a cylindrical screen open at the top, disposed in said casing substantially concentric with said shaft, said screen depending from the upper end of said casing and having a bottom, the lower end of said screen, and said screen bottom, being spaced

away from said casing bottom a major portion of the height of said casing discharge chute; and a tangential discharge chute leading from said screen contiguous to its said bottom, said chutes leading in the same rotational direction from said screen and casing, and means for driving said shaft in said rotational direction, whereby to set up cyclonic air movement within said screen and induce air movement therearound, to set up air discharge flows for the transfer and discharges of said lint and the material cleaned therefrom.

8. A cleaner for an inherently light fibrous material as cotton linters, including an imperforate cylindrical casing, having a bottom, a tangential discharge chute contiguous to said bottom, and a head having a centrally disposed inlet opening; a shaft extending vertically substantially the entire length of said casing and beyond one end thereof, said shaft having a plurality of blades extending therefrom, bearings journaling said shaft, a cylindrical screen open at the top, disposed in said casing substantially concentric with said shaft and said opening, said screen depending from the upper end of said casing, having a bottom closing its lower end, and a tangential discharge chute leading from said screen contiguous to said bottom, the lower end of said screen and its said bottom being substantially spaced from said casing bottom to form an intermediate chamber having a major portion of the depth of said casing chute; said chutes leading in the same rotational direction from said screen and casing; and means for driving said shaft at a high rate of speed in said rotational direction, whereby to set up rotational air movement within said screen and induce air movement therearound and to set up air discharges inducing downwardly spiralling air flow for the segregated transfers and discharges of said lint and the material cleaned therefrom.

9. A cleaner for an inherently light fibrous material as cotton linters, including an imperforate, vertical casing having a bottom and a tangential discharge chute contiguous to said bottom, a cylindrical screen disposed and rigidly supported within said casing, said screen having a top feed opening, a bottom centrally apertured for a shaft, and a tangentially disposed discharge chute adjacent said bottom, said screen bottom and chute being spaced above said casing bottom, and said screen chute extending through a side wall of said casing; a suitably journalled shaft extending substantially from top to bottom of said casing and beyond one end thereof, said shaft being substantially concentric with said screen, and having a plurality of blades extending therefrom, one set of said blades being disposed in the space between said casing bottom and said screen bottom, said chutes leading in the same rotational direction from said casing and screen, and means for driving said shaft in said rotational direction; whereby to set up cyclonic downwardly spiralling air flow within said screen to carry said light material downward and to discharge said material and separately discharge the segregated material.

ARTHUR J. V. WARE.
